T. ALLSOP ET AL

DRYING MACHINE

Filed Aug. 11, 1920

UNITED STATES PATENT OFFICE.

THOMAS ALLSOP AND WALTER W. SIBSON, OF PHILADELPHIA, PENNSYLVANIA,
ASSIGNORS TO THE PHILADELPHIA DRYING MACHINERY COMPANY, OF PHILA-
DELPHIA, PENNSYLVANIA, A CORPORATION OF PENNSYLVANIA.

DRYING MACHINE.

Application filed August 11, 1920. Serial No. 402,841.

To all whom it may concern:

Be it known that we, THOMAS ALLSOP and WALTER W. SIBSON, citizens of the United States, residing in Philadelphia, in the county of Philadelphia and State of Pennsylvania, have invented certain new and useful Improvements in Drying Machines, whereof the following is a specification, reference being had to the accompanying drawings.

The invention relates to machines useful in drying materials capable of being supported upon trays, such for example as chemical products, vegetables, fruits, etc.

15 The object of our invention is the attainment of uniform distribution of the drying medium in and about the trays, so that even drying of the supported materials may be accordingly accomplished. One advantage 20 of our invention is the possibility of dispensing with any special means for effecting such distribution of the drying medium by relegating this function entirely to the trays themselves. This we accomplish by 25 so arranging the trays as to establish a series of intervening channels through which the flow of the drying medium divides evenly into as many different streams while 30 propelled by suitable circulating means.

Other advantages of our invention will 35 become apparent from the detailed description which follows.

Referring to the drawings, Fig. I is a front elevation of a drying machine conveniently 40 embodying our invention, one of the doors of the structure having been shown open so as to expose certain details of the interior.

Fig. II is a cross sectional view through 45 the machine, taken as indicated by the line II-II in Fig. I.

The drying machine herein illustrated is 50 in the form of an enclosure 1 having, in general, as shown in Fig. II, a rectangular cross sectional configuration except for the slope formed by an inclined roof portion 2, which serves a purpose explained hereinafter. At the level of the juncture 55 between the inclined roof portion 2 and the front wall 3, and about at the top of or above the opening for the door in the wall 3 hereinafter described, a horizontal dia- 60 phragm 4 extends across the interior of the enclosure and subdivides the same into a

drying chamber 5, and an auxiliary passage 6, which serves as a by-pass or return conduit for an air circulatory course within the structure. This passage 6 communicates with the front and rear ends of the drying chamber through openings 7 and 8 respectively. The diaphragm 4, it will be noted, 65 terminates short of the front and rear walls of the enclosure, thus leaving the communication openings 7 and 8 just referred to.

The interior of the drying chamber 5 accommodates a multiplicity of horizontal 70 trays 10, adapted to support the materials to be dried. These trays are disposed in relative superimposition, and suitably separated from one another to afford intervening horizontal channels for the passage of the drying medium, so that the latter may readily impinge upon the materials on the trays. In practice, it is preferable to have the trays 75 so mounted as to be capable of being readily removed or interchanged, either while charging or emptying the machine. To this end, the trays are sustained by oppositely facing columnar racks comprising slide- 80 ways formed of angle irons 11, which are fixed to uprights 12, 13 of the structural frame of the machine. By using one or more intermediate uprights such as represented at 13, a number of pairs of oppositely facing cooperating columnar tray racks are 85 provided, said racks being individually accessible from the exterior through doors 14 at the front of the machine. Obviously, this scheme of arrangement may be extended indefinitely, according to practical considerations as to the capacity desired, tray sizes 90 and so on. Angle rails 15 extending across the back of the racks serve as stops to positively determine the position of the trays within the drying chamber so that their 95 front and rear edges are well separated from the enclosure walls, thus affording flow spaces 16 and 17, respectively, by way of which the air may flow into and out of the intervals between the several trays. These flow spaces, it will be noted, are coordinated 100 with the communication openings 7 and 8 between the drying chamber 5 and the auxiliary passage 6. The air within the enclosure is heated by a bank of pipe coils 105 preferably located in the flow space 17 in the rear of the drying chamber.

Circulation of the air is effected by a rotary fan 21, which, in the instance shown, is disposed within a circular opening 22 in a vertical partition 23 spanning the auxiliary passage 6. The fan is fixed upon a shaft 25 journalled in bearings 26, 27 and is adapted to be driven by a pulley 28 attached upon one end of the shaft.

The course of the air circulation within the enclosure created by rotation of the fan 21, is clearly indicated by the arrows in Fig. II. In traversing the drying chamber, the flow is obliged, by reason of the arrangement of the trays hereinbefore described, to divide evenly into a number of horizontal streams, with the result that in passing between the trays it impinges uniformly upon the materials on the trays. The sloping wall 2 serves to facilitate reversal of the direction of flow as the air passes through the auxiliary subdivision 6 of the enclosure. A false floor 29 with a subjacent curtain wall closes off the lower unused portion of the enclosure thereby eliminating what would otherwise be a dead air region and concentrating the flow within the space occupied by the trays.

Having thus described our invention, we claim:

1. A drying machine comprising an enclosure with an opening in front for insertion and removal of sliding trays, and a horizontal diaphragm subdividing the enclosure into a drying chamber and an auxiliary passage; a multiplicity of superposed drying trays in said chamber spaced apart for circulation of drying medium between them, with flow spaces at front and rear of the enclosure; and means for circulating air in the enclosure through said drying chamber and back through said auxiliary passage.

2. A drying machine comprising an enclosure with an opening in front for insertion and removal of sliding trays, and a horizontal diaphragm subdividing the enclosure into a drying chamber and an auxiliary passage; racks in said chamber for sustaining a multiplicity of superposed drying trays spaced apart for circulation of drying medium between them, and stops for so determining the position of the trays on the racks as to leave flow spaces at front and rear of the enclosure; and means in said auxiliary passage for circulating air in the enclosure through said drying chamber and back through said passage.

3. A drying machine comprising an enclosure with an opening in front for insertion and removal of sliding trays, and a horizontal diaphragm above said opening subdividing the enclosure into a drying chamber and an auxiliary passage; racks in said chamber for sustaining a multiplicity of superposed drying trays spaced apart for

circulation of drying medium between them, and stops for so determining the position of the trays on the racks as to leave flow spaces at front and rear of the enclosure; and means for circulating air in the enclosure through said drying chamber and back through said passage.

4. A drying machine comprising an enclosure subdivided by a horizontal diaphragm into a drying chamber and an auxiliary passage serviceable as a return conduit for an air circulatory course within the machine, said diaphragm terminating short of the opposite end walls of the enclosure to afford communication openings between the drying chamber and the auxiliary return passage; in combination with racks for sustaining a multiplicity of slidable, horizontal supporting trays in superimposed relation and at the same time spaced apart to permit circulation of the drying medium therebetween; stops for so determining the position of the trays as to leave, at opposite ends of the drying chamber, flow spaces by way of which the drying medium may pass into and out of the intervals between the trays, said spaces being coordinated with the aforesaid communication openings which connect the drying chamber and the auxiliary return passage; and means for circulating the air within the enclosure.

5. A drying machine in the form of an enclosure comprising a drying chamber; racks for sustaining a multiplicity of slidable, horizontal supporting trays in superimposed relation and at the same time spaced apart to permit circulation of the drying medium therebetween; stops for so determining the position of the trays as to leave at opposite ends of the drying chamber, flow spaces by way of which the drying medium may pass into and out of the intervals between the supporting trays; a bank of heating coils located in one of said flow spaces; an auxiliary passage connecting the flow spaces at opposite ends of the drying chamber and adapted to serve as a return duct for an air circulatory course within the enclosure; and means for circulating the air within the enclosure.

6. A drying machine in the form of an enclosure subdivided by a horizontal diaphragm into a drying chamber, and an auxiliary passage connecting the front and back portion of the drying chamber, said passage serving as a return duct for an air circulatory course within the enclosure; in combination with racks for sustaining a multiplicity of slidable, horizontal trays in superimposed relation within the drying chamber and at the same time spaced apart to permit circulation of the drying medium through the intervening horizontal channels thus established; stops for so determining the position of the trays as to leave at op-

- posite ends of the drying chamber flow spaces by way of which the drying medium may pass into and out of the intervals between the supporting trays; heating coils 5 located in the flow space at the rear of the drying chamber; and means for circulating the air in the enclosure through the drying chamber and back through the aforesaid passage.
- 10 7. A drying machine comprising an enclosure with a compartment therein for the material to be dried, and a passage directly connecting the top of said compartment with a side thereof; means in said compartment 15 for supporting material to be dried in horizontal tiers; and means for circulating air in said enclosure, with flow either way through said compartment and return through said passage.
- 20 8. A drying machine comprising an enclosure divided to form a drying chamber and a return air passage, one side of the enclosure being open, guides in the drying compartment whereby trays may be inserted 25 through the open side and supported upon the guides and located substantially centrally of the chamber to form vertical passages at the front and rear ends of the trays, and means for circulating air between the 30 trays, around the ends and through the return passage.
9. A drying machine comprising an enclosure divided to form a drying compartment and a return passage, means for supporting a series of trays to provide vertical 35 air passages at either end, a bank of heating coils in one of said vertical passages adjacent to one of the ends of the trays, and means for circulating air therein and 40 for drawing the air along the heated passage, through the coils between the trays and
- around the opposite ends of the trays returning through the adjacent vertical passage.
10. A drying machine comprising an enclosure having a pair of openings in one side wall, doors for closing said openings, a series of guides behind each opening, whereby short trays may be inserted through said openings upon the guides and disposed 45 with their ends in spaced relation to the sides of the inclosure to form vertical air passages, a heating means in one of said passages, and means for circulating air within the inclosure and between the trays. 50
11. A drying machine comprising a casing having a slanting top wall forming a low front wall and a high back wall, a horizontal partition within the casing defining a lower drying chamber and an upper return air passage, a series of horizontal guides in the drying chamber, trays supported on the guides of a length to provide vertical spaces between the ends of the trays and the walls of the casing, a bank 55 of heating coils in one of said passages, a vertical partition in the upper return air passage, and a fan located in said opening to circulate the air through the heating coils, between the trays, around the ends of the 60 latter, through the air passage, along the slanting top wall and through said opening in the order named.
- In testimony whereof, we have hereunto signed our names at Philadelphia, Pennsylvania, this 10th day of August, 1920. 65
